DESIGN FOR A WASHING MACHINE

Charles K. Woodin, Newton, Iowa

Application June 5, 1937, Serial No. 69,693

Term of patent 7 years

To all whom it may concern:

Be it known that I, Charles K. Woodin, a citizen of the United States, residing at Newton, in the county of Jasper and State of Iowa, have invented a new, original, and ornamental Design for a Washing Machine, of which the following is a specification, reference being had to the accompanying drawing, forming a part thereof.

The figure is a front perspective view of a washing machine showing my new design.

The right side of the machine is similar to the front and the back is like the left side, except that the position of the power leg is reversed.

I claim:

The ornamental design for a washing machine substantially as shown and described.

CHARLES K. WOODIN.
